United States Patent Office.

THOMAS BISHOP AND DANIEL AGNEW, OF VINCENNES, INDIANA.

Letters Patent No. 98,547, dated January 4, 1870.

IMPROVEMENT IN BRICK-MACHINES.

The Schedule referred to in these Letters Patent and making part of the same.

To all whom it may concern:

Be it known that we, THOMAS BISHOP and DANIEL AGNEW, of Vincennes, in the county of Knox, and in the State of Indiana, have invented certain new and useful Improvements in Brick-Machines; and do hereby declare that the following is a full, clear, and exact description thereof, reference being had to the accompanying drawings, and to the letters of reference marked thereon, making a part of this specification.

The nature of our invention consists in the construction and general arrangement of a "brick-machine" and its moulds.

In order to enable others skilled in the art to which our invention appertains, to make and use the same, we will now proceed to describe its construction and operation, referring to the annexed drawings, in which—

Figure 1 is a perspective view of the brick-machine;

Figure 2 is a bottom view of the same;

Figure 3 is a plan view of the mould;

Figure 4 is an end view of the same; and

Figure 5 is a vertical cross-section, taken through line *x* *x*, fig. 3.

Figure 6 is an enlarged vertical cross-section of the die-plate.

Figure 7 is a side view of the adjustable bars upon which the inner end of the mould-rack rests.

Figure 8 is a side view of the presser-wings.

Figure 9 is a plan view of one of the cutters or workers, and

Figure 10 is a cross-section of the same, taken through line *y* *y*, fig. 9.

A represents the receptacle for the mud, or mud-gum, as it is generally called, resting upon wheels *B* *B*, so that it can be moved readily to any place desired. In the drawings we have represented the mud-gum as being square, but in a full-sized machine we intend to fill the front corners to a circle, to fit the press-wings, which will prevent the mud from squeezing up, and will force it into the mould.

At the front side, in the bottom of the mud-gum *A*, is placed the die-plate *C*, the front edge of the under side of which is bevelled, as shown in fig. 6, at *a*, so that on the principle of a wedge it will press the gravel-stones in the clay into the brick, and will thus prevent the breaking of the mould by the gravel catching between the edge of the mould and the corner of the die-plate, which is often the case in other machines.

Through the centre of the mud-gum *A* is a shaft, *D*, upon which, directly above the bottom of the mud-gum, are placed two press-wings, *E* *E*. The outer edge of the press-wings is raised, and the inner edge curved to a level, in order to drive the mud from the

shaft in the centre toward the outer rim of the mud-gum, thereby causing them to fill the mould better.

Above the press-wings *E* *E*, on the shaft *D*, is placed a series of curved and bevelled cutters or workers, *F* *F*, which, when they revolve with the shaft, work the mud downward in the mud-gum toward the press-wings.

From the corners of the mud-gum extend rods *b* *b*, inward toward the centre, between which rods the workers or cutters *F* move, so as to cut up the mud and prevent clogging.

On each side, a suitable distance below the bottom of the mud-gum *A*, is pivoted a bar or lever, *G*; the front end of which is slotted vertically, and fastened by a screw passing through said slot. By this means the bar *G* may be adjusted at will.

At a suitable point on said bar is a notch or recess, in which the foot *d* of the rack *H* is placed.

The rack *H* is formed of a frame, of any suitable size, having rollers *e* *e* running across the same, from the front side to a cross-bar, *f*, in the frame, which cross-bar is placed at such a distance from the rear side of the frame as to form a space at the rear end of the frame equal to the width of the mould.

In this space is placed a series of rollers, *g* *g*, running at right angles from the rollers *e* *e*.

By this construction of the rack there will be little or no friction of the moulds, as the moulds are always on rollers, they being put on endwise on the rollers *g* *g*, for which purpose a roller, *h*, is placed in the side of the machine, and when filled they are moved outward lengthwise across the rollers *e* *e*, by means that will be hereinafter described.

The front or outer end of the rack *H* is raised and lowered to adjust the mould to the under side of the die-plate *C*, by means of a bent bar, *I*, having a crank, *i*, at one end.

Above the opening where the moulds are moved out after being filled, is placed a roller, *J*, covered with cloth, for the mould to pass out under. This roller should be creased about one-sixteenth of an inch over each partition of the mould, and will press the brick into the mould, smooth the top, and do away with all feather-edge. The cloth being wet prevents the mud from adhering to the roller.

The journals of the roller *J* pass through slots in standards *K* *K*, and have rubber springs above them in said slots, so as to allow the roller to yield slightly, if necessary.

On the opposite side of the machine from that on which the roller *J* is situated, is placed a bumper, *L*, for the mould to strike against when inserted. This bumper consists of a bent bar inserted in suitable heads, and adjusted by set-screws at any point desired, as shown in fig. 2.

Our mould M is constructed of a frame, k, having vertical grooves in its sides suitable distance apart to form a brick between each set of grooves.

Slats or boards l l are fastened under the frame k, forming the bottoms of the moulds, which bottoms fill up the space between the vertical grooves mentioned.

A metal frame, m, is then fitted around the lower edge of the frame k, in such a manner as to be even with the under side of the bottom l.

In the frame m are secured a series of partitions, n n, which fit in the grooves on the sides of the frame k, and are of the same height as this latter frame.

The ends of the frame m are provided each with a vertically slotted plate, o, and an ear, p, and said frame is then attached by means of a screw passing through the slot in each plate o, into the ends of the frame k.

After the mould is filled, to empty the same, turn it bottom up, press the thumbs on the bottom, catching the ears p p at the ends, and raising the partitions n n.

Above the mud-gum A, upon the shaft D, is placed a collar with two cams, N N, which, as the shaft revolves, each in its turn operates upon a friction-roller, O, placed on the under side of a slotted sliding bar, P, which moves on the upper side of the machine, and is guided in its movement by means of flanged rollers r r, as shown in fig. 1.

The cams N N bulge considerably from the eye, so that they give a straightforward push, instead of pressing sideways on the slotted slide when it starts to push it forward by the friction-roller.

Upon the slide P are secured three bars, R R, forming a triangular frame, to which, on each side of the machine, is pivoted a lever, S.

This lever extends down along the side of the machine, and is at a suitable point pivoted to another lever, T, which in turn is pivoted to the side of the machine.

One end of the lever T is slotted, and adjusted at any point desired by a set-screw, s, so as to lengthen or shorten the stroke, to suit the distance the mould is to be moved when it is filled.

The lower ends of the levers S S are connected by a bar, V, which, after the mould has been filled, forces the mould out each time the cam N moves the slide P.

Under the bottom of the mud-gum A, at the rear side, is a standard, W, having a rod, t, extending horizontally forward.

This rod is surrounded by a spiral spring, v, which, at its rear end, bears against a slide, w, connected by a rod or chain with the bar V, so that when said bar has moved the mould out, the spring v will cause the said bar V, and with it the levers S S, and slide P, to move back to their original position, ready to be again operated by the cam.

Having thus fully described our invention,

What we claim as new, and desire to secure by Letters Patent, is—

2. The combination of the rack H, adjustable levers G G, and bent bar I, with crank i, when constructed and operated substantially as and for the purposes herein set forth.

2. The combination of the standards K K and cloth-covered roller J, having its yielding bearings in said standards, and with openings placed above the journals, substantially as and for the purposes herein set forth.

3. The mould M, composed of the frames k m, loose bottom l, partitions n n, slotted plates o o, and bars p p, constructed and arranged as and for the purposes herein set forth.

4. The die-plate C, having the front edge of its under side bevelled, substantially as and for the purposes herein set forth.

5. The arrangement of the cams N N, friction-roller O, slide P, frame R, levers S S, and bar V, all substantially as and for the purposes herein set forth.

6. The arrangement of the rod t, spring v, and slide w, connected with the bar V, substantially as and for the purposes herein set forth.

In testimony that we claim the foregoing, we have hereunto set our hands, this 6th day of November, 1869.

THOMAS BISHOP.
DANIEL AGNEW.
